Primary Examiner — Ian Simmons*Assistant Examiner* — Rhea Shields**CLAIM**

The ornamental design for a biopsy system console, as shown and described.

DESCRIPTION

FIG. 1 is a perspective view of a biopsy system console showing the new design;

FIG. 2 is a top view of the biopsy system console, with the cover in the closed position;

FIG. 3 is a top view of the biopsy system console, with the cover in an open position;

FIG. 4 is a front view of the biopsy system console;

FIG. 5 is a left side view of the biopsy system console;

FIG. 6 is a right side view of the biopsy system console; and, FIG. 7 is a rear view of the biopsy system console.

In the drawings, the broken lines depict unclaimed subject matter only and form no part of the claimed design.
